UNITED STATES PATENT OFFICE

2,493,188

SUPPORTING FRAME FOR POSTAGE METERS

Harold Francis Ford, Cirencester, England

Application June 26, 1948, Serial No. 35,456
In Great Britain April 8, 1947

2 Claims. (Cl. 235—1)

1

This invention relates to machines for printing and issuing pre-paid postage or revenue stamps, labels, tickets and the like and to the kind wherein printing is effected by a rotary element which after making contact with an inking device cooperates with pressure means to print on a strip of paper drawn from a supply roll and to eject the printed portion to a position where it can be detached. Machines of this general character are well known for use in issuing tickets on passenger vehicles, an example being that described in the prior United States Patent Specifications Nos. 1,920,085 and 2,137,915.

The object of the present invention is to provide improvements in the construction and arrangement of a machine having the general features indicated in the preceding paragraph, such improvements being designed to enable adhesive stamps for parcel post purposes, pre-paid tickets, price labels and similar articles to be issued. To adapt the machine for these purposes, certain features such as stage and class printing mechanism and associated parts are eliminated.

According to the invention a machine for printing and issuing stamps, labels, tickets or the like of the kind above described is characterised by a stationary framework in which the operative part of the machine is detachably mounted, a single hand operated setting device to adjust the value printing die to any one of a predetermined range of values, and counting mechanism to record only the total value and total number of the stamps or other articles issued.

Reference will now be made to the accompanying drawings which show a machine constructed according to the invention and in which—

Fig. 1 is a perspective view of the complete machine and its support,

Fig. 2 is a side elevation of the machine,

Fig. 3 is a plan corresponding to Fig. 2,

Fig. 4 is a front elevation of the machine partly in section,

Fig. 5 is a detail view of the counter mechanism, and

Fig. 6 shows representation of two stamps issued by the machine.

The construction illustrated is that of a machine for printing and issuing adhesive stamps for parcel post purposes and comprises the operative part of the machine enclosed within a casing 1 which is removably mounted in a supporting frame 2 carried upon a base plate 3 capable of being affixed to the surface of a desk or post office counter.

Within the casing 1 are mounted a rotary print-

2

ing element 4 and a pressure roller arranged to co-operate therewith in known manner; an inking device 5 disposed adjacent the printing element; counting mechanisms 6, 7, 8 for recording respectively the values in shillings and pence and the total number of stamps issued, the counters being duplicated at 6a, 7a and 8a for checking purposes and to provide against the failure of a counter; and transmission mechanism for adjusting the value die in the printing element and for adjusting the position of the actuating means for the counters to accord with the value of the stamp to be printed.

A paper supply roll 9 is disposed freely within a chamber 10 forming an extension of the supporting frame 2 and having a transparent wall 11 to enable the user of the machine to see when the paper supply is approaching exhaustion. The transparent wall 11 is removable to enable an exhausted paper spool to be removed from the chamber 10. The upper ends of the side walls of the chamber 10 are shaped to engage an extension 12 of the casing 1 which is formed with a slot on its underside through which the free end 15 of the paper strip enters the extension 12, passes between the printing element and pressure roller and, following the course indicated in broken lines in Fig. 2, emerges through an opening 13 where it projects as a printed stamp as shown at 14 in Fig. 1. The stamp can be detached by tearing it along the blade 15 having a serrated edge disposed parallel to one edge of the opening 13. When the paper spool becomes nearly exhausted its weight becomes insufficient to maintain the paper strip taut and it would tend to enter the machine and no longer be visible. To prevent this happening there is provided within the chamber 10 a plate 16 hingedly mounted at 17 and caused to bear at its free end upon the surface of the paper strip, as shown in Fig. 2, by a spring 18 whose end bears upon the underside of the plate 16.

The machine enclosed within the casing 1 is freely supported by the upper edges of the frame 2 and is retained thereon against displacement by forming the upper rear portion 19 of the frame as a component movable about hinges 20 arranged, when in the position shown in Fig. 2, to overlap partly the casing 1 and to be held in that position by hooks 21 engaging eyes 22 projecting from the ends of the frame portion 19. To prevent displacement of the casing 1 relatively to its support a bar 23 connected by a spring 24 to the base plate 3 is formed with a slot to engage over a stud 25 on the casing 1. A

bent portion 26 at the upper end of the bar 23 enables it to be lifted against the resistance of the spring 24 to disengage it from the stud 25 when it is desired to detach the casing 1 from the frame 2.

The rotary printing element 4 has a variable value printing die which is set to print the value required by operating a finger dial 27 mounted on the front upper part of the casing 1. Around the peripheral portion of the dial are circular apertures 28 adjacent each of which is marked one of the values which the machine is designed to print. The dial 27 is mounted on a short shaft 29 the lower end of which carries a toothed pinion 30 meshing with a rack bar 31 slidably mounted in guides 32 and arranged at one end to be engaged by means carried by the printing element towards the end of its rotation to service the setting mechanism. The rack bar also carries a yoke 33 to adjust the position of toothed discs 34, 35 and 40 along a shaft 36 to transmit appropriate impulses to the counters. The extent of movement imparted to the value printing die and the discs 34, 35 and 40 is controlled by a stop 37 by which the finger of the operator is arrested after partial rotary movement of the dial 27 has been effected.

The discs 34 and 35 are arranged to operate the pence counters 7 and 7a and each disc bears a number of teeth appropriate to one of the pence values which the machine is arranged to print. One of the discs 34 becomes operative when a pence value only is to be printed. When a one shilling stamp is being printed a plain disc 38 comes opposite the toothed wheels 39 which operate the counters 7 and 7a so that no movement is transmitted to them, while the unit shilling disc 40 operates the toothed wheels 4 of the shillings counters 6 and 6a. When combined shilling and pence values are being printed one of the discs 35 becomes operative to actuate the toothed wheels 7 and 7a and one of the discs 40 is moved into position to actuate the toothed wheels 41 of the counters 6 and 6a. In all positions a striker 42 carried by the printing element 4 operates the toothed wheels 43 of the counters 8 and 8a which record the total number of stamps issued by the machine. The discs 34, 35 and 38 are slotted as shown at 44 in Fig. 5 to pass over a fixed comb plate 45 which prevents re-adjustment of the discs along the shaft 36 until that shaft has completed a rotation to print and eject a stamp from the machine.

To deal with normal inland parcel postage rates the range of values may commence at 6d and increase by units of one penny up to 1/5d, thereby providing twelve values which includes postage plus registration rates as well as postage only. Alternatively, and according to particular requirements, the machine may be arranged to print any selected twelve values from 1d to 11/11d. The finger dial and the corresponding variable printing die are normally arranged so that in the normal rest position, tickets of the lowest value will be printed. The dial as shown is arranged so that it is temporarily retained in a selected position to enable a number of stamps all of the same value to be issued. Alternatively, the dial can be arranged for automatic return to initial position after each individual issue. Instead of the dial the value setting may be effected by a cranked handle, lever or any other device capable of being moved to any of a number of predetermined positions and its movements transmitted to the value die.

The indications given by the counters can be observed through windows 46 (Fig. 5) disposed in apertures in the casing 1.

The operation of printing and ejecting a stamp is effected by rotating a handle 47 projecting from one end of the machine and mounted on the end of the shaft 36, the handle being provided with release and stop means to compel a complete rotation once rotational movement of the handle has been commenced. This release and stop means is preferably that described in our concurrent application No. 598,938.

To enable a fresh spool of paper to be inserted a hinged door 48 is provided on the casing 1 having a quick lock and release closure device which operates under the pressure of a spring also utilised to bear upon and guide the paper strip. This arrangement eliminates any necessity for threading the paper strip into the machine.

Examples of stamps which can be produced by the machine above described are shown in Fig. 6. In these stamps there are only two variable elements, the first being the date at 49 the die for printing which is adjusted daily by hand, and the second being the value which in one stamp illustrated is a pence value shown at 50 and in the second illustration a combined shilling and pence value shown at 51.

I claim:

1. A casing construction adapted for the detachable mounting of a unitary stamp printing and issuing machine in a fixed location, said unit machine comprising a body part having extended side portions with a special contour, said casing comprising a base, a hollow box-like body part upstanding from said base, said body part having a front end wall and a rear end wall and a top opening into which the unit machine is passable, said casing also having left and right side walls, said side walls having bearing surfaces cut into their upper edges to a contour which matches the contour of the extended sides of said body part, said body part being adapted to be supported upon said bearing surfaces to support the unit machine in said opening in transversely extending relation between the said side walls, a clamping section swingably incorporated in the said rear end wall, for movement towards and away from said opening, said swingable section comprising a top portion defining a transversely extending edge portion adapted, in the inwardly swung position of the section, to lie in overlying juxtaposition and substantially flush with respect to a plane surface of the machine unit which extends below and above the top opening and is disposed at an angle with the planes defined by the said side walls, said contoured bearing surfaces, in co-operation with the angled plane surface and with a front wall upper edge of the casing upon which the front end of the machine casing rests, being so adapted as to hold the lower portion of the machine unit located within the casing in an enveloping manner while leaving the remaining upper exposed machine portion available for the operation thereof, and latch means on said casing adapted for releasable engagement with said machine unit to hold the unit firmly positioned upon the casing for its required operating functions.

2. A combination machine unit and casing construction as defined in claim 1, wherein said latch means comprise a bar, a spring connecting one end of said bar with the base of the casing in spaced relation to the outside of the front casing wall, and co-operable connecting means on the

front of the machine unit and the opposite end of the said bar adapted for engagement with one another to hold the machine unit resiliently down into operative position on top of the said casing.

HAROLD FRANCIS FORD.
